Primary Examiner — Eric Goodman(74) *Attorney, Agent, or Firm* — Pearne & Gordon LLP(57) **CLAIM**

The ornamental design for a I.V. flow rate regulator, as shown and described.

DESCRIPTION

FIG. 1 is a perspective view of my new invention;
 FIG. 2 is a right side view thereof;
 FIG. 3 is a left side view thereof;
 FIG. 4 is a front view thereof, a rear view being a mirror image thereof;
 FIG. 5 is a top view thereof; and,
 FIG. 6 is a bottom view thereof.
 The broken line showing in FIGS. 1-5 is to illustrate portions of the article and form no part of the claimed design.
